MATCH DISPLAY STAND

Joseph Shapiro, St. Louis, Mo., assignor to Universal Match Corporation, St. Louis, Mo., a corporation of Delaware

Application May 23, 1949, Serial No. 2,811

Term of patent 14 years

(Cl. D80—9)

To all whom it may concern:

Be it known that I, Joseph Shapiro, a citizen of the United States, residing at the city of St. Louis, State of Missouri, have invented a new, original, and ornamental Design for a Match Display Stand, of which the following is a specification, reference being made to the accompanying drawing, forming a part thereof.

The figure is a perspective view of a match display stand showing my new design. The opposite side of the design is substantially similar in appearance to the side shown.

I claim:

The ornamental design for a match display stand, substantially as shown and described.

JOSEPH SHAPIRO.
